UNITED STATES PATENT OFFICE

WALTER M. CROSS, OF KANSAS CITY, MISSOURI, ASSIGNOR, BY MESNE ASSIGNMENTS, TO GASOLINE PRODUCTS COMPANY INC., OF WILMINGTON, DELAWARE, A CORPORATION OF DELAWARE

APPARATUS FOR TREATING HYDROCARBONS

Application filed October 31, 1923. Serial No. 672,020.

This invention relates to an apparatus for treating hydro-carbon oils and refers particularly to the treatment of oils in which relatively heavy oils are converted to produce lighter oils of low-boiling points.

The invention contemplates, broadly, the heating of the oil to a conversion temperature, the conversion or cracking of the oil under such pressure that the oil is kept in a liquid phase and substantial vaporization during the conversion or cracking operation is prevented, the subsequent release of pressure and the consequent vaporization of the converted oil, the separation of the light and heavy ends, the re-boiling and further vaporization of the heavy ends and the subsequent condensation and separation of the vapors.

The invention further contemplates the preliminary heating of the charging stock and the use of the stock to assist in the separation of the light and heavy ends before referred to.

In the drawings there is illustrated one embodiment of the invention which will be used in the description of the apparatus as well as the method, but it is to be understood that the invention is not limited to this particular embodiment as many changes in the details of construction may be made without departing from the spirit of the invention, or without exceeding the scope of the claims.

Figure 1 is a diagrammatic view of the illustrative apparatus;

Figure 2 is an enlarged detail sectional view of the dephlegmator tower and evaporator, and

Figure 3 is a plan view of the same.

Referring to the drawings the oil to be treated is introduced into the apparatus from a tank 1 which contains the charging stock. It passes from this tank through the pipe 2 to the suction side of a pump 3. From this pump the oil is forced through a pipe 4 into a coil 5 which is arranged within the dephlegmator tower 6 (see Fig. 2) the operation and function of which latter will hereinafter be explained. From the coil 5 the oil passes through a pipe 7 to the furnace

8 in which the oil is raised to a conversion or cracking temperature. The coil 5 may be isolated from the pipes 4 and 7 by means of valves 9 and the oil by-passed around the coil through a pipe 10 which, likewise, is provided with a valve 11. This latter valve may be closed to cause the oil to flow through the coil at which time the valves 9 are open or the latter valves may be closed and the former opened to permit the oil to be by-passed around the coil and directly from the pipe 4 to the pipe 7 through which it is led to the furnace 8. It is also to be noted that if the supply tank 1 is made comparatively small it will constitute a mixing chamber or heat exchange for preheating the charge by the hot condensate from the dephlegmator, and thus obtain additional thermal economies.

Here in the furnace the oil is passed through a series of coils 12, being forced therethrough at a rate sufficient to permit the oil to be raised to a conversion or cracking temperature but to prevent any substantial cracking and deposit of carbon within the coils. The oil enters the coils at the top of the furnace and leaves at the bottom so that as it passes therethrough it is progressively subjected to higher temperatures, the bottom of the furnace being, of course, nearer to the fire-box.

As the oil passes from the coils 12 it enters the conversion chamber 13 through a pipe 14 in which it is held without substantial reduction of temperature under pressure, in liquid phase, for a sufficient length of time to insure its complete conversion or cracking. The oil is held in this conversion chamber in an enlarged body until it assumes an equilibrium or a stable rearrangement of the molecular bodies. This may be accomplished by either maintaining the oil stationary within the chamber for a definite period (which is determined by experimentation) by keeping the valve 15 closed, or on the other hand the valve 15 may be slightly cracked to permit the oil to flow through the conversion chamber 13 at a relatively slow rate.

This conversion of the oil in the chamber 13, by the molecular rearrangement in a

liquid phase without any substantial vaporization except of the incondensable gases which create pressure in the chamber, results in what I term a synthetic crude oil containing an increased percentage of low-boiling point oils which may be easily extracted by subsequent distillation.

This synthetic crude is forced through the pipe 16 and the valve 15, which has hereinbefore been referred to, into the evaporator 17 where the pressure is reduced to such an extent as to result in the vaporization of the oil by the heat contained within the oil.

The dephlegmator tower 6 is associated with the evaporator 17 so that the vapor will pass from the latter to the former. The particular association which is illustrated in the drawing is such that the dephlegmator tower is mounted directly on the evaporator and the vapors pass through purifiers from the latter to the former, but it is to be understood that this particular co-relation of the evaporator and dephlegmator is not essential as it is only essential that they be so arranged that the vapor may pass from the evaporator to the dephlegmator.

Referring, however, to the embodiment disclosed in the drawings, the dephlegmator tower includes an outer shell 18 which is provided at its lower end with a vapor space 19, said space being produced by a partition 20.

Communication is established between the evaporator 17 and this vapor space 19 through a pipe 21 and purifiers or liquid removers 22. These latter operate to permit the vapor to pass into the pipe 21 to separate the entrained liquid globules from the vapor, this separated liquid being returned to the lower part of the evaporator 17 through pipes 23 where it is accumulated and from which it automatically flows off through a pipe 24 the valve 25 of which is automatically operated by float control 26 to a suitable receiver. Furthermore, the accumulated liquid may be permitted to flow off through the manually operable valve 27 which is provided with an operating handle 28.

Referring now to the dephlegmator tower which is more particularly illustrated in Figure 2, and which is similar in principle to that described and claimed in my co-pending application No. 674,678, filed November 14, 1923, the container 29 is mounted within the outer shell 18. This container is spaced from the bottom and top of the tower and from the shell 18 which latter spacing results in the production of a passage 30 between the container and the shell through which the rising vapor passes. The coil 5 which has hereinbefore been referred to, is located within this space 30 and surrounds the container 29.

Likewise, a second coil 31 through which a cooling medium may be circulated surrounds this container which latter coil is, however,

not co-extensive with the coil 5 inasmuch as it terminates short of the upper end thereof. The vapor which rises between the shell 18 and the container 29 through the space 30, is caused to follow a convolute path by means of a convolute baffle 32 which follows the course of the coils.

In order that the vapor may pass from the vapor space 19 to the upper end of the tower a plurality of pipes 33 extend through the partition 20 and are provided with elbows 34 at their upper ends. These pipes establish communication between the vapor space 19 and the upper portion of the tower, and the elbows at their upper ends prevent any condensate falling back through the pipes into the vapor space 19.

A pipe 35 leads from the upper end of the tower and the vapors pass into this pipe through purifiers or liquid removers 36 similar to those used in the evaporator. These purifiers are provided with liquid return pipes 37 which extend into and adjacent to the lower end of the container 29 in which latter the liquid separated from the outgoing vapor is deposited until it reaches a predetermined height at which time it overflows through a pipe 38 to the lower end of the tower and accumulates above the vapor space 19 on the partition 20. It will be noted that this accumulation is around the pipes 33 so that, as the vapors pass up through the latter, the heat from the vapors is distributed throughout the accumulated liquid.

As the vapors which pass from the vapor space 19 through the pipes 33 rise in a convolute path around the container 29 and the cooling coils, the higher boiling point vapors are condensed out and fall back into the lower end of the tower. The lower boiling point vapors pass upwardly and after having passed to the purifiers 36 escape through the pipe 35, the separated entrained liquid being returned to the container 29 from whence it is subsequently conveyed through the pipe 38 and mixed with the condensate which accumulates in the lower end of the tower. The liquid which accumulates in the container 29 preliminarily receives heat by the rising vapors and when it is deposited in the lower end of the tower it together with the accumulated condensate, is subjected to a re-heating and re-boiling which results in a further vaporization of the oil. This accumulation at the bottom of the tower is automatically drawn off through a pipe 39 when it reaches a predetermined height and may be returned to the charging stock tank. It, however, may be by-passed around this charging stock tank and forced directly to the heating coils by closing the valve 40 and opening the valve 42. The manipulation of the valves 40 and 42 determines whether or not the oil passing through the pipe 39 enters the charging stock tank or

is by-passed around the same to the pipe 41 and enters the furnace coils by way of inlet line 7. The pump 42' serves to overcome the pressure differential existing in pipes 39 and 7. That is to say, it picks up the low pressure oil in pipe 39 and forces it into the high pressure zone obtaining in pipe 7.

The vapors passing from the upper end of the dephlegmator tower through the pipe 35 are conveyed to a cooler 43 where the vapors of a relatively high boiling point are condensed out. This condensate, together with the uncondensed vapor passes to a gas separator 44 from which the condensate flows to a storage tank 45, its flow being controlled by an automatically operable valve 46 which permits an out-flow when a predetermined level is reached in the separator 44. The uncondensed vapors pass from this separator through a pipe 47 to a compressor 48, the suction side of which compressor is also connected, through a pipe 49, to the condensate storage tank 45. The pipe 47 is provided with a valve 50 and the pipe 49 with a valve 51 for a purpose which will later appear.

The vapor is forced by the compressor 48 through a condenser 52 and thence into a separator 53 which, because of its relation to the compressor, operates, preferably under a pressure of from 5 to 10 atmospheres. The lower end of this separator is connected to the storage tank 45 by a valved pipe 54, and the upper end by a valved pipe 55 to a fuel gas collector 56.

The pipe connection 49 with the valve 51 therein makes it possible by closing the valve 50 and opening the valve 51 to draw the gas from the storage tank 45 and pass it through the compressor to the condensing elements.

I claim:

1. An apparatus for treating hydrocarbon oils, which includes a heating coil adapted to receive oil from a supply tank, a cracking chamber, an evaporator and a dephlegmator successively connected, a conduit connecting the supply tank with the heating coil, a portion of which conduit is located within the dephlegmator, means for forcing the oil from the supply tank through the conduit to the heating coil, means for returning the condensate collected in the dephlegmator to the heating coil, and a separate by-pass connection around the portion of the conduit in the dephlegmator whereby the oil may be charged without preheating directly to the heating coil.

2. An apparatus for treating hydrocarbon oils, which includes a heating coil adapted to receive oil from a supply tank, a cracking chamber, an evaporator and dephlegmator successively connected, a conduit connecting the supply tank with the heating

coil, a portion of which is located within the dephlegmator, means for forcing the oil from the supply tank through the conduit to the heating coil, a separate by-pass connection around the portion of the conduit in the dephlegmator whereby the oil may be bypassed without preheating, and means for removing the condensate from the dephlegmator and passing it into the said conduit to the heating coil.

3. An apparatus for treating hydrocarbon oils comprising a cracking unit in which oil may be cracked under heat and pressure, an evaporator and a dephlegmator successively connected, a supply tank, a conduit connecting the supply tank with the cracking unit, a portion of which conduit forms a coil within the dephlegmator, means for forcing the oil from the supply tank through the dephlegmator coil, means for returning the heated condensate collected in the dephlegmator directly to the cracking unit and a by-pass connection around the portion of the conduit in the dephlegmator whereby oil may be bypassed without preheating to the cracking unit.

4. An apparatus for treating hydrocarbon oils which includes a heating coil adapted to receive oil from a supply tank, a cracking chamber, an evaporator and a dephlegmator successively connected, a conduit connecting the supply tank with the heating coils, a portion of which conduit is located within the dephlegmator, means for forcing the oil from the supply tank through the conduit to the heating coils, means for automatically returning the condensate collected in the dephlegmator to the supply tank and means positioned in the bottom of the dephlegmator to effect a heat exchange between streams of vapors directed thereto from the evaporator and the condensate separated from the vapors in the dephlegmator and accumulated as a body therein.

5. An apparatus for treating hydrocarbon oils which includes a heating coil adapted to receive oil from a supply tank, a cracking chamber, an evaporator and a dephlegmator successively connected, a conduit connecting the supply tank with the heating coils, a portion of which conduit is located within the dephlegmator, means for forcing the oil from the supply tank through the conduit to the heating coils, means for automatically returning the condensate collected in the dephlegmator to the supply tank and a separate by-pass connection around the portion of the conduit in the dephlegmator whereby the oil may be charged without preheating directly to the heating coil.

WALTER M. CROSS.
